UNITED STATES PATENT OFFICE.

DANIEL W. MEACHAM, OF MCADENSVILLE, NORTH CAROLINA.

AUGER-HANDLE.

SPECIFICATION forming part of Letters Patent No. 512,384, dated January 9, 1894.

Application filed May 2, 1893. Serial No. 472,684. (No model.)

To all whom it may concern:

Be it known that I, DANIEL W. MEACHAM, a citizen of the United States, residing at McAdensville, in the county of Gaston and 5 State of North Carolina, have invented a new and useful Auger-Handle, of which the following is a specification.

This invention relates to auger handles, and has for its object to provide a handle 10 wherein different sized auger-shanks may be removably mounted and readily adjusted, and which can readily be taken apart and stored within a tool-chest.

With these and other objects in view, the 15 invention consists of the construction and arrangement of the parts thereof as will be hereinafter more fully described and claimed.

In the drawings: Figure 1 is a perspective view of the improved handle showing an auger in connection therewith, together with a 20 lever for operating the same. Fig. 2 is a central longitudinal vertical section of the handle on an enlarged scale. Fig. 3 is a perspective view of the parts of the handle disconnected from each other.

Similar numerals of reference indicate corresponding parts in the several figures of the drawings.

Referring to the drawings, the numeral 1 25 designates a central sleeve or thimble, having the interior portions of the opposite ends formed with right and left screw-threads 2 and 3, and extending vertically therethrough is an angular or square opening 4. Removably and adjustably engaging the opposite screw-threaded ends of the sleeve are handle-sections 5 and 6, having the exterior portions of their inner ends formed, respectively, with right and left screw-threads 7 and 8, and their 30 extreme inner end edges beveled, as at 9, to form biting edges 10. The said handle-sections are tubular and formed of piping with the outer ends closed, and the said sleeve is also preferably formed of piping. Through 35 the handle-sections at suitable distances from the sleeve extend openings 11, adapted to be engaged by a removable hand-lever 12, whereby the said handle-sections may be adjusted firmly and securely. The shank of the auger 40 is provided with one or more notches 13 in

opposite sides thereof and is fitted removably in the angular or square opening 4. The two handle-sections 5 and 6 are then screwed inwardly into the sleeve 1 until the biting edges 10 engage the notches on the opposite sides 55 of the shank of the auger, to thereby hold the latter against displacement from the sleeve. By this means it will be seen that no intermediate mechanism is required to hold the auger shank in the sleeve, and that the inner 60 edges of the handle-sections engage the auger shank directly. If desired, one or more of the sleeves may be employed, but through the adjustment of the handle-sections the opening 4 could be made large enough to accommodate various sizes of auger shanks. 65

In storing the improved handle, the handle-lever is placed within the same and the whole can then be readily put away within a tool-chest or other place, thereby taking up a very 70 small amount of room and providing for readily transporting the same from place to place.

Changes in the form, proportion, and the minor details of construction may be resorted to without departing from the principle or 75 sacrificing any of the advantages of this invention.

Having described the invention, what is claimed as new is—

1. In an auger handle, the combination of a 80 central sleeve with an angular opening therethrough and right and left screw-threads on the interior of the opposite ends thereof, handle-sections with correspondingly-screw-threaded inner ends with terminating biting 85 edges, and an auger shank having notches in the opposite sides thereof adapted to be directly engaged by the inner biting edges of the said handle-sections, substantially as described. 90

2. In an auger handle, the combination of a central sleeve with an angular opening therethrough and right and left screw-threads on the interior of the opposite ends thereof, tubular handle-sections having correspond- 95 ing exterior screw-threads at the inner ends of the same to engage the aforesaid screw-threads, and inner opposite bevels to form biting edges, said handle-sections also being provided with openings, a hand-lever for en- 100

gaging said openings of the handle-sections, and an auger shank having notches in the opposite sides thereof adapted to be directly engaged by the biting edges of the said handle-sections, said auger shank being removably mounted in the angular opening of the sleeve, substantially as described.

In testimony that I claim the foregoing as my own I have hereto affixed my signature in the presence of two witnesses.

D. W. MEACHAM.
